BLINKER SIGNALING DEVICE

John V. Horr, North Tarrytown, N. Y., assignor
to Einson-Freeman Co., Inc., Long Island City,
N. Y., a corporation of Delaware

Application August 26, 1943, Serial No. 500,155

6 Claims. (Cl. 35—14)

My present invention relates generally to signaling devices, and has particular reference to a device of the "blinker" type.

A general object of my invention is to provide a signaling device of such simplified structure that it may be manufactured almost entirely of simple inexpensive sheet material such as cardboard or the like. A more particular object is to provide a structure and mode of operation which permits the device to assume an unusually small and compact form adapted to be held in and operated by one hand of a user.

The present improved device has been designed primarily for instructional purposes, it being intended that large quantities of the device may be manufactured speedily and at low cost, for distribution to trainees in the armed forces, and others, to enhance the teaching of signaling generally and the art of "blinker" signaling in particular. Because of its small and inexpensive nature, the device may also find utility as an educational toy. Nevertheless, since it is a complete signaling device by means of which messages and signals may be transmitted from one person to another, and since certain features of the invention are not necessarily restricted to a device of reduced size, it will be understood that certain phases of the invention may be considered to relate to signaling devices generally.

The present improved structure consists essentially of a pair of superposed relatively slidable flat front and back members, the front member having a series of adjacent spaced apertures therein, the back member being provided on its front surface with spaced light and dark areas which are so arranged that relative endwise movements of said members will bring either the light or the dark areas into matching registry with said apertures. The apertures preferably assume the form of parallel slits arranged in a group which conjointly defines a sort of circular "spot," and the markings on the back member are correspondingly shaped and arranged. Thus, if the outer surface of the front member is of dark character, the contemplated relative movements of the members will result in making this "spot" alternately dark and light, whereby code messages may be transmitted to an observer at a distance in much the same manner as such messages are transmitted by large-size blinker signaling devices. However, whereas the conventional large-size devices usually employ a beam of light from an artificial source, and require pivoted movements of louvres or the like and all the mechanism and accessories which such an action calls

for, the present device is essentially composed of only the two front and back members referred to.

The relatively slidable front and back members of the present device are associated with a means of resilient yieldable character for urging the members into one condition of registry, whereby signaling may be effected by intermittently forcing or pressing the members into the other condition of registry against the action of the resilient means.

A more particular object of the present invention is to provide a device of this general structural and operational character in which all of the parts may be composed of portions of a single unitary blank of sheet material such as cardboard or the like, and in which the contemplated resilient effect may be achieved either without the employment of any extraneous elements or material whatsoever, or by means of a simple spring reinforcement of unusually simple and non-critical material. This desirable result is achieved, briefly, by a special design which defines a springy panel having one edge portion articulated to one of the front and back members, and having another edge portion in fixed positional association with the other of said members. This springy panel is so arranged that it normally lies flat behind the back member and is adapted to buckle resiliently outwardly when said edge portions are depressed toward each other.

I achieve the foregoing objects and advantages, and such other objects and advantages as may hereinafter appear or be pointed out, in the manner illustratively exemplified in the accompanying drawings, in which:

Figure 1 is a perspective view of a signaling device constructed in accordance with the present invention;

Figure 2 is an enlarged cross-sectional view taken substantially along the line 2—2 of Figure 1;

Figure 3 is a view similar to Figure 2 showing the relationship of the parts when pressure is exerted upon the device during the signaling operation;

Figure 4 is an enlarged cross-sectional view taken substantially along the line 4—4 of Figure 1;

Figure 5 is a plan view of the blank of which the present device may be composed;

Figure 6 is a perspective view of the first step in assembling the device;

Figure 7 is a view similar to Figure 6 showing a subsequent step;

Figure 8 is a view similar to Figure 7 showing a subsequent step; and

Figures 9 and 10 are face views of the device illustrating the changes in its appearance when it is used for signaling purposes.

The front member 10 consists of a flat blank of sheet material, such as cardboard, and is provided with a series of spaced adjacent apertures 11 which I have illustratively shown in the form of parallel slits conjointly defining a sort of circular "spot." The front member 10 is preferably substantially rectangular and I have illustratively shown it in the form of a square. So that the general nature and capabilities of my invention may be more fully appreciated, it may be mentioned that a satisfactory and highly efficient device may be constructed with this square no more than about two inches long.

Arranged behind the member 10 and in sliding contact therewith is a back member 12 which is provided on its front surface with spaced light and dark areas 13 (see Figure 8). Where the apertures 11 assume the form of slits as shown in Figure 1, the markings on the back member 12 are of corresponding striped configuration. These markings are so arranged that reciprocating endwise movements of one of the members relative to the other will alternately bring either the light areas or the dark areas 13 into matching registry with the apertures or slits 11.

The unique features of the present improved structure can be best explained by reference to Figures 5, 6, 7 and 8.

In Figure 5 I have shown a single blank of sheet material, such as cardboard or the like, which is cut and shaped to define the various hinged sections and panels shown.

Hinged to one edge 15 of a panel 14 is a reinforcement panel 16 which is adapted to be folded over onto the panel 14, as shown in Figure 6, and permanently secured thereto by adhesive means or otherwise, thus forming a strengthened two-ply bracing panel. For the sake of clearness, this two-ply bracing panel will hereafter be designated by the single reference numeral 14. A recess 17 initially cut in the blank across the hinge line 15 provides this bracing panel 14 with a cut-out along one edge for a purpose presently to be described.

Hinged to an adjacent edge of the panel 14, as at 18, is a section of substantially rectangular shape which ultimately defines the front member 10 having the apertures or slits 11 therein.

Along the opposite edge 19 of the panel 14 is an attachment flap 20 of relatively narrow width.

Along the fourth edge 21, the bracing panel 14 is hingedly connected to a rectangular panel 22 of slightly increased length, this panel being the springy one which ultimately provides for the resilient action which contributes to the desired operation of the device. To enhance this springy action it may be desirable to lay a resilient reinforcement element in the form of a flat leaf spring 23 longitudinally along the midportion of the panel 22, but the use of this spring is not absolutely essential and the inherent resilience of the material of which the panel 22 is made (such as cardboard or the like) may be sufficient by itself to achieve the desired result.

When the parts are assembled, as will be presently described, the cut-out 17 serves to accommodate an end portion of the reinforcement element 23 so as to avoid the possibility of a slight binding or impeding action which might otherwise take

place, but if the element 23 is dispensed with, the cut-out 17 may also be omitted.

Articulated to the springy panel 22, along the edge 24 opposite the edge 21, is a substantially rectangular part or section which ultimately defines the rear or back member 12 previously referred to. The markings on the front face of this member are shown most clearly in Figure 8.

In constructing the device, the sections 14 and 16 are first permanently secured together, as hereinbefore mentioned, and as indicated in Figure 6, to define a relatively stiff reinforced bracing panel. The unit shown in Figure 6 is then adjusted into the relationship of Figure 7 by swinging the bracing panel 14 upwardly along the hinge line 21 so as to bring it into overlying relationship to the springy panel 22. The member 12 is then folded downwardly along the hinge line 24 so that it lies over the panel 14 as shown most clearly in Figure 8. Finally, the attachment flap 20 is turned down over the face of the member 12, and the member 10 is brought downwardly to overlie this face, and is secured by adhesive means or otherwise to the attachment flap 20.

This results in providing a structure in which the bracing panel 14 and the front member 10 are held together in superposed relationship to define a flat pocket between them within which the member 12 is movable to permit endwise reciprocation. More particularly, it will be observed that the member 10 and the panel 14 are held together along their side edges 18 and 19, thus providing an open-end pocket into which the member 12 extends.

It will also be observed that the springy panel 22 lies flat behind the bracing panel 14. By virtue of its connection to the panel 14 along the edge 21, this edge portion of the panel 22 is secured in fixed positional association with the front member 10, while the opposite edge portion 24 is articulated or hinged to the back member 12.

The outer surface of the front member 10 may be either dark or light, but it is preferably of dark character as indicated most clearly in Figures 9 and 10. Also, the markings on the front surface of the back member 12 are preferably arranged so that under normal conditions the darker areas show through the apertures of slits 11, thus imparting to the face of the device a normal appearance as shown in Figure 9. By pressing the edge portions of the springy panel 22 toward each other, the back member 12 may be shifted so as to bring the lighter areas 13 into a position in which they show through the slits 11, and the front face of the device then presents an appearance as shown in Figure 10. This adjustment of the parts is accompanied by a resilient outward buckling of the resilient springy panel 22, as shown most clearly in Figure 3. As a result, when the pressure is released, this panel restores the parts immediately to the normal condition.

It will thus be observed that I have provided a signaling device of unusually compact and simple structural nature. Except for the slight adjustments which are brought about during use of the device, there are no moving parts and hence no mechanism that might get out of order. The desired springy effect can be achieved without the use of any metal or rubber springs or other extraneous elements, and even where the reinforcement 23 is deemed desirable, it is of such a character that it may be composed of a material other than metal. Furthermore, the resilient action of the springy panel is simple, efficient, and reliable,

and serves also as a guide for the reciprocating movements of the member 12, effectively maintaining this member in proper alignment at all times. The fact that the entire device may be composed of a single piece of flat sheet material, and may be held together by simple adhesive means makes the structure easy and inexpensive to manufacture.

In general, it will be understood that the details herein described and illustrated to explain the general nature of the invention may be modified by those skilled in the art without departing from the spirit and scope of the invention as expressed in the appended claims.

Having thus described my invention and illustrated its use, what I claim as new and desire to secure by Letters Patent is:

1. In a blinker signaling device, a pair of superposed relatively slideable flat front and back members, the front member having a series of adjacent spaced apertures therein, the back member being provided on its front surface with spaced light and dark areas so arranged that relative endwise movements of said members will bring either the light or the dark areas into matching registry with said apertures, a bracing panel connected to the front member and lying behind the back member, and a yieldable resilient means for normally urging said members into one of said conditions of registry, said means comprising a springy panel having spaced edge portions articulated respectively to said back member and said bracing panel, said front and back members and said bracing panel and springy panel being integral parts of a single blank of sheet material.

2. In a blinker signaling device, a pair of superposed relatively slideable flat front and back members, the front member having a series of adjacent spaced apertures therein, the back member being provided on its front surface with spaced light and dark areas so arranged that relative endwise movements of said members will bring either the light or the dark areas into matching registry with said apertures, a bracing panel connected to the front member and lying behind the back member, and a yieldable resilient means for normally urging said members into one of said conditions of registry, said means comprising a springy panel having spaced edge portions articulated respectively to said back member and said bracing panel, said springy panel normally lying flat behind said bracing panel and being adapted to buckle resiliently outwardly when said edge portions are pressed toward each other.

3. In a blinker signaling device to be held in and operated by one hand of a user, a substan-

tially rectangular flat bracing panel, a flat front member overlying said panel and hinged to one edge thereof, said front member having a series of adjacent spaced apertures therein, a flat 5 springy substantially rectangular panel hinged to an adjacent edge of said bracing panel and lying behind the latter, and a flat back member hinged to the opposite edge of said springy panel and extending into the space between said front member and said bracing panel, said springy panel being slightly longer than said bracing panel so that manual pressure upon its opposite edge portions will cause outward buckling thereof and will shift the back member endwise relative to the 10 front member, said back member being provided on its front surface with spaced light and dark areas so arranged that in one of its positions the dark areas and, in another of its positions the light areas will be brought into matching registry with the apertures in said front member.

15 4. In a blinker device, the combination set forth in claim 3, the resilience of said springy panel being enhanced by a relatively narrow leaf spring extending lengthwise of the springy panel and arranged on its under side.

20 5. In a blinker device, the combination set forth in claim 3, the resilience of said springy panel being enhanced by a relatively narrow leaf spring extending lengthwise of the springy panel and arranged on its under side, the bracing panel having 25 a cut-out adapted to accommodate one end of said leaf spring.

6. In a blinker signaling device to be held in and operated by one hand of a user, a substantially rectangular flat bracing panel, a flat front 30 member overlying said panel and having a series of adjacent spaced apertures therein, said bracing panel and front member being secured to each other along the opposite side edges of the bracing

35 panel so as to form an open-end pocket between them, a flat back member slidably mounted in said pocket and provided on its front surface with spaced light and dark areas so arranged that reciprocating endwise movements of the back member will alternately bring the light areas and the 40 dark areas into matching registry with said apertures, and a flat springy substantially rectangular panel lying behind the bracing panel and hinged at opposite edges to the bracing panel and to said 45 back member respectively, said springy panel being of such a length that pressure on said hinges will cause outward resilient buckling of said springy panel as the back member is moved endwise in one direction relative to said front

50 55 member.

JOHN V. HORN.
